LIQUID FUEL BURNER

Ralph W. DeLancey, Meriden, Conn., assignor to
 The Miller Company, Meriden, Conn., a corporation of Connecticut

Application March 1, 1945, Serial No. 580,435

5 Claims. (Cl. 158—91)

1

The present invention relates to combustion apparatus, and is more particularly directed toward liquid fuel burners employing a vaporizing pot type burner.

A common and well known form of vaporizing pot type burner employs a sheet metal vaporizer into which the liquid fuel flows and a perforated wall through which air passes, either under forced or natural draft, to provide air for mixture with fuel vapors and the combustion of the fuel. In burners of this type the walls are thin so that jet directional control is unsatisfactory. There is also a tendency especially with fuels with substantial carbonaceous residues for such residues to accumulate.

It is an object of the present invention to improve this general class of pot burners in such a way that they are able to more completely dispose of carbonaceous residues than heretofore.

The present invention contemplates the employment of a pot or vaporizer usually in the form of a casting provided with thick enough walls to permit the drilling of sloping holes through the walls so as to direct air jets downwardly into the bottom of the pot. In normal operation of the burner these sloping air holes may be closed and the air enters into the combustion chamber through the holes in a perforated sleeve above the pot.

According to the present invention means are provided whereby the air supply to the holes in the perforated sleeve can be cut off and all the air entering the interior of the burner be sent down through the downwardly extending holes in the pot walls. This action takes place at the time when the fuel control mechanism for supplying fuel to the burner is turned off at the end of a high fire operation or soon thereafter. The liquid fuel remaining in the pot along with carbonaceous residues and the pot are hot because of the high fire operation. The draft, either natural or artificial, causes strong, hot air jets to be formed by the air coming in through the inclined holes so that heated air and flame may be available to burn away the carbonaceous residues.

The accompanying drawings show, for purposes of illustrating the present invention, several embodiments in which the invention may take form, it being understood that the drawings are illustrative of the invention rather than limiting the same.

In these drawings:

Figure 1 is a sectional view, somewhat diagrammatic, illustrating a form of construction employ-

ing a thermally controlled metering valve and thermally controlled baffle for controlling the air flowing into the burner, the parts being shown in full lines in position for high fire operation and in dotted lines in position when the burner is not operating or is at pilot or on low fire;

Figure 2 is a fragmentary view illustrating the baffle in the latter position;

Figure 3 illustrates a modified form of construction with parts in the same position as Figure 2; and

Figure 4 illustrates a form of construction employing electrical controls.

In Figure 1 the room thermostat 10 controls the circuit for a metering valve 11 having a metering valve stem 12 operated by a thermostat 13 under the control of a heater 14. A second heater 15 in parallel with the heater 14 actuates a bimetallic thermostat 16. The oil line 17 from the metering valve is adapted to deliver fuel to the pot 18 of the burner. This pot is preferably made of cast iron and has downwardly and inwardly sloping drillings 19. Above the pot 18 is a perforated sleeve 20 of usual construction. In the drawings a natural draft burner is indicated, the air supply coming through a housing 21 which surrounds the pot and perforated sleeve.

A baffle ring 22 is carried above the pot 18 and has a flanged portion 23 adapted to rest on the top of the pot and close off the holes 19. This ring 22 is connected through rods 24 with a spider ring 25. A lever 26 pivoted at 27 and provided with a counterweight 28 extends from the center of the spider 25 to the plunger 29 adapted to be operated by the thermal element 16.

When the room thermostat 10 is calling for heat the thermal elements 14 and 15 are heated and the parts in the position indicated in full lines in Figure 1. When, however, the room thermostat 10 is satisfied it opens the circuit, the metering valve gradually closes down and the thermal bar 16 is also bent down by the cooling of the thermostat. The latter operation causes the baffle or ring 22 to lift up away from the holes 19 in the wall of the pot 18 and the ring 22 is brought against flanged rings 30 and 31 carried by the housing 21 and perforated sleeve 20, respectively, so as to close off the passage of air up to the holes or perforations in the sleeve 20.

With this change in draft conditions all the draft must pass through the holes 19. This creates strong jets of heated air, unlike the lazy air streams produced by perforations in sheet metal, and these strong jets are directed down

toward the center of the bottom of the pot. This heated air will have high oxygen content and with the residual heat in the pot and the heat produced by burning the fuel it is possible to consume a great deal more of the carbonaceous residue than in pot burners in which no provision is made for getting pure air down into the bottom of the pot. Also the air jets facilitate the maintenance of the pilot flame and the complete combustion of the fuel supplied for the pilot flame.

In the modified form of construction illustrated in Figure 3 the damper ring 33 is arranged to close off the space to the perforations in the perforated sleeve 20, but is not arranged to close off the openings 19 so that with this construction some of the air is directed down into the bottom of the pot at all times.

The arrangement shown in Figure 4 is the same as that shown in Figures 1 and 2 so far as the burner itself is concerned and the same reference characters are applied. Here the fuel supply is under the control of a solenoid valve 40 and the lever 26 is under the control of a solenoid 41.

It will also be understood that the sequence of operations according to which the draft conditions are changed when going from high fire operation to pilot can be effected manually when a manual control metering valve is employed.

Since it is obvious that the invention may be embodied in other forms and constructions within the scope of the claims, I wish it to be understood that the particular forms shown are but a few of these forms, and various modifications and changes being possible, I do not otherwise limit myself in any way with respect thereto.

What is claimed is:

1. Combustion apparatus comprising a burner of the vaporizing pot type adapted for intermittent high fire operation and having two vertically separated groups of spaced apart inlet air openings in the side wall thereof, the lowest group of openings sloping downwardly and inwardly and when open directing air jets toward the burner bottom, fuel supply and regulating mechanism for controlling the flow of liquid fuel to the burner, and air control means operating concurrently with the fuel regulating mechanism for shutting off the air supply to the lowest group of openings and opening the upper openings to the air supply when the fuel flow is regulated for high fire and for opening the lowest group of openings and shutting off the upper openings when the firing rate is reduced so that hot air jets may be directed toward the residue in the vaporizer after reduction of fuel supply.

2. Apparatus as in claim 1, wherein the fuel regulating means includes a metering valve having an electrically heated thermostatic operator,

and the air control means includes a similar operator.

3. Apparatus as in claim 1, wherein the fuel regulating means and the air control means include solenoids in parallel with one another.

4. Combustion apparatus comprising a burner of the vaporizing pot type having an annular side wall adapted for intermittent high fire operation and having two vertically separated groups of spaced apart inlet air openings in the aforesaid side wall thereof, the lowest group of openings sloping downwardly and inwardly and when open directing air jets toward the burner bottom, fuel supply means, an air chest communicating with all the openings and forming the sole source of air for combustion, and a baffle ring in the air chest and movable between two positions to direct air through the lowest group of openings only when in one position or through the upper openings only when in the other position.

5. Combustion apparatus comprising a vaporizing pot burner having a burner bowl with an annular wall of substantial thickness and which has annularly disposed inwardly and downwardly inclined holes extending therethrough, a sheet metal sleeve extending upwardly from the bowl, an air chest forming housing about the sleeve and burner bowl, the sleeve having perforations at various levels for supplying air from the air chest under normal draft conditions to mix with the vapors rising from the burner bowl, and a baffle ring in the air chest housing above the level of the inclined holes and movable from a position where it opens the holes in the burner bowl wall and closes off air supply to the perforations in the sleeve, to a position where it closes the holes in the burner bowl wall and admits air to the perforations in the sleeve.
